United States Patent Office.

NICHOLAS S. VEDDER, OF TROY, NEW YORK.

Design No. 3,861, dated February 22, 1870.

DESIGN FOR A STOVE-PLATE.

The Schedule referred to in these Letters Patent and making part of the same

To all whom it may concern:

Be it known that I, NICHOLAS S. VEDDER, of the city of Troy, in the county of Rensselaer, and State of New York, have invented and produced a new and original ornamental Design for Plates of a Cooking-Stove, of which the following is a specification, reference being had to the accompanying photographic illustration.

The distinguishing feature of this design is the compound central ornament *b* or *c* and ornamental border *d* or *e*, shaped and arranged on a door or doors, or on

a plate or plates of a cooking-stove or range, so as to appear as represented in the aforesaid photograph.

What I claim as my invention or production, and desire to secure by Letters Patent, is—

The design for a door or doors or a plate or plates of a cooking-stove or range, as herein specified and shown by the accompanying photographic illustration.

NICHOLAS S. VEDDER.
